COMBINED CIGARETTE SNUFFER AND ASH-TRAY LINER OR SIMILAR ARTICLE

Harry W. Hollister, 89 Thayer St.,
New York, N.Y. 10040

Filed May 10, 1971, Ser. No. 142,106

Term of patent 14 years

Int. Cl. D27—03

U.S. Cl. D85—2 H

FIG. 1.

FIG. 2.

FIG. 3.

FIG. 4.

FIG. 1 is a top perspective view of a combined cigarette snuffer and ashtray liner or similar article, showing my new design;

FIG. 2 is a side elevational view, the appearance being the same from all sides;

FIG. 3 is a top plan view; and

FIG. 4 is a bottom plan view thereof.

I claim:

The ornamental design for a combined cigarette snuffer and ashtray liner or similar article, substantially as shown and described.
